UNITED STATES PATENT OFFICE.

MAX DOERFEL, OF KLINGENTHAL, GERMANY.

HARMONICA.

SPECIFICATION forming part of Letters Patent No. 449,755, dated April 7, 1891.

Application filed December 10, 1890. Serial No. 374,201. (No model.)

To all whom it may concern:

Be it known that I, MAX DOERFEL, a subject of the King of Saxony, and a resident of Klingenthal, in the Kingdom of Saxony, in 5 the German Empire, have invented certain new and useful Improvement in Harmonicas, of which the following is a full, clear, and exact specification.

Heretofore covering and protecting the 10 reeds in harmonicas has been effected by shields made of metal, wood, hard rubber, or the like, which were secured to either side of the base-board by means of screws, pins, or the like. Each reed-plate had to be covered by a special 15 shield, the front and rear sides of which formed at the same time parts of the mouth-pieces. This method of constructing harmonicas has several disadvantages, among 20 which may be mentioned, first, the necessity of covering each reed-plate separately; secondly, the amount of work and loss of time and money occasioned thereby; thirdly, the composition of the mouth-piece of no less than three parts—*i. e.*, the base-board, the upper 25 shield, and the under shield—by which the lips of the blower sometimes were severely damaged, and, fourthly, the liability of the harmonica to get out of repair, inasmuch as the shields got loose and were lost, and consequently 30 the reeds freed from any protection were bent and broken, thus rendering the whole instrument perfectly worthless in very short time. All these inconveniences have been entirely overcome by the invention illustrated 35 in the accompanying drawings, in which similar letters denote similar parts throughout the several views, and in which—

Figure 1 is a vertical section taken on the line M M of Fig. 3. Fig. 2 is another vertical 40 section taken on the line C C of Fig. 3. Fig. 3 is an upper view of the harmonica. Fig. 4 is a front view of the same. Fig. 5 is a vertical section through a modification.

The new instrument is constructed as follows: The base-plate *a*, made of wood, metal, 45 papier-maché, rubber, celluloid, or any other suitable material, and provided with blow-holes *i*, carries at either side a reed-plate *b*, having longish openings *h* and reeds *c*, as

usual. Now, instead of covering the upper 50 and under side of the harmonica each separately by a shield, a shell is formed of celluloid, xylonite, hard rubber, or any other artificial material, or of metal or papier-maché, the breadth of said shell corresponding with 55 the breadth of the base-plate and with the reed-plates, as clearly shown in Fig. 2. In thickness the shell exceeds considerably that of the other parts, so as to form sounding-chambers by means of which the intensity, 60 quality, and clearness of the tones are much increased and improved. The whole base-plate with its, appurtenances, is put into the shell and fastened to it nearly completely by the elastic force of the shell itself, but may 65 be secured finally by means of screws or pins at its rear side. There are at the front side of said shell holes *f*, corresponding with those of the base-plate *a*, and the upper and under edges of the front side are bent somewhat 70 inward, so as to form very convenient and comfortable places for the lips. Thus the mouth-piece is ready, consisting of only one piece of perfect smoothness and without the smallest projection, forming, as explained 75 above, one piece with the two shields and with the rear side. The shell cannot possibly get lost, and thus no getting out of order of the music-work itself can happen, and all the inconveniences and deficiencies of harmonicas of the old construction mentioned in the preface are entirely overcome.

The properties of a variety of materials do not allow the manufacture of shells in one piece closed at all sides. In such cases the 85 modification shown in Fig. 5 may be used. Instead of covering the rear side of the instrument too, the two ends of the shell may be bent horizontally and secured to the base-plate by means of rivets, as easily to be understood from the drawings. By this arrangement the same advantages are obtained as by the original construction.

Having thus fully described the nature of this invention, what I desire to secure by Letters Patent of the United States is—

In a mouth-harmonica, the combination, with the base-plate *a*, having a reed-plate *b*

at either side, of a shell *d*, consisting of one piece and covering the reed-plates, and the blow-holes *i* in the base-plate, said shell forming the mouth-piece, the protecting-plates for the reeds *c*, and the sounding-boards, substantially as described.

In testimony whereof I have signed this

specification in the presence of two subscribing witnesses.

MAX DOERFEL.
